UNITED STATES PATENT OFFICE

BRENT S. DRANE, OF CHARLOTTE, NORTH CAROLINA

AUXILIARY SEAT

Application filed January 20, 1928. Serial No. 248,173.

The invention relates to that type of auxiliary seat colloquially known as "lazy backs". Such devices are intended to be used in conjunction with a backless bench or stool 5 in such a manner as to give a measure of support to the sitter's back.

The principal object of the invention is to provide an effective device of this nature at the least possible cost, and to this end I propose to construct such seats entirely of suitable fabric material without the use of any supporting frames. A seat so constructed may be formed from a single blank, or it may be built up from a plurality of blanks, or 15 again, the bodies of the seats may be formed during their original manufacture to the desired specifications.

I have used above the term "fabric material" and it is to be understood that I use this 20 expression in its broadest sense as meaning any suitable felted, woven, knitted or netted material composed of animal, vegetable, or any other suitable fibers.

Further, this material may be water- 25 proofed, reenforced, or treated in any other desirable manner.

With these general premises in view, I shall proceed to describe a number of embodiments of my invention with reference to the accompanying drawings, wherein—

Fig. 1 shows a perspective view of one form of seat according to the invention.

Fig. 2 shows in plan view a single blank from which the seat of Fig. 1 is formed.

Fig. 3 is a perspective of another form of seat.

Fig. 4 is a plan view of the blank from which the seat of Fig. 3 is formed.

Fig. 5 is a perspective of still another form 40 of seat with parts dis-associated.

Fig. 6 is a plan view of the blank from which the seat of Fig. 5 is formed.

Fig. 7 is a perspective from another angle of the finished seat according to Fig. 5.

Fig. 8 is a perspective of another form of auxiliary seat shown positioned on the seat of a stool.

Fig. 9 is a perspective of a further embodiment of the invention shown attached to the 50 seat of an ordinary stool.

Fig. 10 is a section of Fig. 9 taken on a line from the front to the rear of the auxiliary seat.

Fig. 11 is a perspective showing the parts of the auxiliary seat of Fig. 9 as dis-associated. 55

Fig. 12 is a face view of a section of re-enforced fabric material, and

Fig. 13 is a section of Fig. 12 taken transversely of the re-enforcing elements. 60

Referring to the drawings, it will be seen that the seat according to Fig. 1 comprises a bottom portion 15, a back portion 16, and side portions 17 and 18. A seat of this general form may be secured by properly folding blanks of various forms. In this instance a quadrilateral blank, such as is shown in Fig. 2, is utilized, and this blank is folded as follows:

The four sides of the blank are designated 19, 20, 21 and 22, and initially the margin at side 19 is folded over and downwardly on line 23, and thereupon tips 24 and 25 are folded over and downwardly on lines 26 and 27. Now by bringing lines 28 and 29 over against 70 equal lines 30 and 31, respectively, rearward bellows folds are created along lines 32 and 33, so that triangle 22, 28, 32, lies over triangle 22, 30, 32, and triangle 20, 29, 33, lies over triangle 20, 31, 33, this being permitted 75 by flexures along lines 15', 16', and 16''. These two triangular lateral wings are now folded under the bottom portion 15 and secured, the extreme portions 34 and 35 of tips 24 and 25 being folded along lines 36 and 37 and 80 brought on top of bottom 15. Flap 38 is now folded over on bottom 15 and tips 34 and 35 and suitably secured in this relation. It will be noted that back portion 16 is inclined at an acute angle to bottom 15. This is for 85 the reason that in use the angles between side portions 17 and 18 and back portion 16 tend to straighten out, thus throwing the upper margin of back portion 16 rearwardly.

In use, the outer margins of the back, bottom and side portions form what is in effect a strap extending under the legs and across the back of the user. Since most of the strain is taken by the marginal areas, these are re-enforced by doubling, in the manner described, 100

to form binding means for the edges. The form shown may be conveniently made of kraft paper or the like, which may be water-proofed and re-enforced if desired. By way of example, the seat according to Fig. 1 may be made of two-ply fabric material as shown in Figs. 12 and 13, the material being re-enforced by filamentary re-enforcing elements, such as strings 39 secured between the outer and inner plies 40 and 41, the plies being secured together by a waterproof adhesive. In using such a re-enforced fabric material, the blank is so cut that when folded the filamentary elements will run horizontally across back portion 16, and obliquely between the back portion and the bottom portion through the side portions.

When in dis-use the side portions 17 and 18 are bellowed inwardly along lines 17' and 18', so that the device will occupy very little space.

The auxiliary seat according to Fig. 3 is likewise made of a single blank, in this instance in the form of an oblong, having sides 12, 43, 44 and 45. In this instance the seat portion proper is really defined by the dotted lines 46, 47, 48 and 49, the sections between these lines and the extreme edges being lapped over to form the re-enforced edges. In forming the seat, corner 50 is folded over along the line 51 and corner 52 along line 53. The lower left hand square is given a forward fold along line 54, and the lower right hand square along line 55, and the resulting triangular portions designated as 56 and 57 in Fig. 3 are brought into the position there shown on bottom portion 58, flexure also taking place along lines 59, 60, 58', 65' and 65''. When the seat is in dis-use side portions 61 and 62 are bellowed inwardly along lines 63 and 64 so that back portions 65 may be brought down against the body portion.

The seat according to Fig. 5 again is composed of a single blank, this time in substantially the form of the letter T having sides 66, 67, 68, 69, 70, 71, 72 and 73. The upper margin is first folded forward on line 74 against the body of the blank, and thereupon the tips are folded forwardly along lines 75 and 76 against the body. The lower margin is folded upwardly and inwardly along line 77. The side wings are now swung inwardly along lines 78 and 79, whereupon the whole upper portion is folded toward seat portion 80 along line 81, and corners 82 and 83 are folded under the bottom portion along lines 84 and 85, extreme tips 74' and 74'' being brought on top of the bottom portion. The corners of the blank between line 74 and lines 67 and 73 are brought on top of the bottom portion 80. Lines 84 and 85 up to their points of intersection with lines 75 and 76, respectively, are equal to sides 71 and 69. Consequently, the triangular portions 86 and 87 included respectively between lines 73, 73', and 75, and 67,

67' and 76, extend forwardly beyond the bottom portion 80, and are folded back against the latter in the manner shown in Fig. 5 and secured thereto. The sides may be bellowed inwardly along lines 84' and 85'.

The described frameless auxiliary seats will be most effective when they fit the person of the user somewhat closely, and for this reason they are preferably made in a number of sizes.

As an alternative the perimeters of the outer margins may be made adjustable, and means for effecting such adjustability are shown by way of example in Fig. 7. According to this figure, back portion 88 has secured thereto two parallel eyeletted strips 89 and 90, these latter being connected together by means of a string 91. If the seat is too large it may be made smaller by tightening the string. In so doing the back portion intermediate the straps will be bellowed inwardly, the bellowed portion being flattened out when the seat is in use.

It is to be understood that this adjustable feature is equally applicable to the devices shown in Figs. 1 and 3, and that the re-enforced fabric of Figs. 12 and 13, which has been shown in application only in Fig. 7, is equally applicable to the devices according to Figs. 1 and 3.

The seats shown in Figs. 1-5 and 7 are preferable as to form as compared to the sheet shown in Fig. 3 for the reason that, as clearly indicated, the back portion and side portions are inwardly inclined from the vertical—their planes produced would converge at a point above the bottom portion. This design accentuates the strap effect which I have mentioned above and a "bag" effect, so to speak, is secured rather than a "tray" effect as in Fig. 3. When the bottom portion and back portion are so proportioned that their outer margins engage the user just behind the bent knee and just above the hips, respectively, a maximum degree of support is afforded.

According to Fig. 8, the auxiliary seat is composed of a netted or reticulated fabric body 92 formed to the proper shape, the margins being securely bound with a non-elastic element 93. The bottom portion of binding 93 may be secured by means of cords 94 and 95 to the legs of a stool 96.

In Figs. 9 to 11 the seat is composed of flexible fiberboard, canvas, or other suitable material, and composed of two blanks 97 and 98. Blank 98 constitutes the seat portion and is in the shape of a major segment of a circle. Blank 97 constitutes the back and side portions and is in the shape of a minor segment of a larger circle. The straight edge of segment 97 is bent inwardly to form a flange 99 so as to underlie the margins of the circular portion of seat portion 98, and the flange and margins are suitably secured together. The circular margin of element 97 is bent back upon itself and so secured as to form

a guideway for draw strings 100, and margin 101 of bottom portion 98 is bent back underneath and secured to provide a re-enforced edge. Draw strings 100 are adapted to be secured to the legs of a stool 102 as indicated in Fig. 9. It is obvious that instead of draw strings any other suitable attachment devices may be used.

While I have necessarily shown and described some illustrative embodiments of my invention, it is to be understood that I do not confine myself to the exact details disclosed, but that the scope of my invention is determined in the following claims.

15 I claim:—

1. A frameless auxiliary seat of fabric material, said seat comprising a bottom portion, a back portion, and side portions, said side portions comprising webs joining the outer margin of said back portion with the outer margin of said bottom portion, the outer margins of all of said portions forming in effect a strap adapted to extend under the legs and across the back of the user, and means to adjust the perimeter of said seat along said margins.

2. A frameless auxiliary seat of fabric material, said seat comprising a bottom portion, a back portion, and side portions, said side portions comprising webs joining the outer margin of said back portions with the outer margin of said bottom portion, the outer marginal sections of said back and side portions being turned on themselves and secured to form re-enforcing binding means, the outer margins of all said sections forming in effect a strap adapted to extend under the legs and across the back of the user, and means to adjust the perimeter of said seat along said margins.

40 3. A frameless auxiliary seat of fabric material, said seat comprising a bottom portion, a back portion, and side portions, the planes of said side portions and back portion being upwardly convergent, said side portions comprising webs joining the outer margin of said back portion with the outer margin of said bottom portion, the outer margins of all of said portions forming in effect a strap adapted to extend under the legs and across the back of the user.

45 4. A frameless auxiliary seat of fabric material, said seat comprising a bottom portion, a back portion, and side portions, the planes of said side portions and back portion being upwardly convergent, said side portions comprising webs joining the outer margin of said back portion with the outer margin of said bottom portion, the outer margins of all of said portions forming in effect a strap adapted to extend under the legs and across the back of the user, and means to adjust the perimeter of said seat along said margins.

50 5. A frameless auxiliary seat of fabric ma-

terial, said seat comprising a bottom portion, a back portion, and side portions, the planes of said side portions and back portion being upwardly convergent, said side portions comprising webs joining the outer margin of said back portion with the outer margin of said bottom portion, the outer marginal sections of said back and side portions being turned on themselves and secured to form re-enforcing binding means, the outer margins of all said sections forming in effect a strap adapted to extend under the legs and across the back of the user.

6. A frameless auxiliary seat of fabric material, said seat comprising a bottom portion, a back portion, and side portions, the planes of said side portions and back portion being upwardly convergent, said side portions comprising webs joining the outer margin of said back portion with the outer margin of said bottom portion, the outer marginal sections of said back and side portions being turned on themselves and secured to form re-enforcing binding means, the outer margins of all said sections forming in effect a strap adapted to extend under the legs and across the back of the user, and means to adjust the perimeter of said seat along said margins.

7. A seat cover formed from a single sheet of flexible material folded to provide a seat portion, side portions and a back portion, one of said portions consisting of a plurality of lapped folds extending substantially perpendicularly to the other of said portions and to the side portions.

8. A seat cover formed from a single sheet of material folded to provide a seat portion, angular side portions and a back portion, one of said portions consisting of a plurality of lapped folds extending substantially perpendicularly to the other of said portions and to the side portions, said side portions having means whereby they may be folded inwardly between the seat and back portions.

In testimony whereof I have hereunto set my hand.

BRENT S. DRANE.
